UNITED STATES PATENT OFFICE.

GEORGE H. ELLIS, OF ST. PAUL, MINNESOTA.

HEAT-INSULATING UNIT.

1,228,763.

Specification of Letters Patent.

Patented June 5, 1917.

Original application filed March 16, 1914, Serial No. 842,959. Divided and this application filed March 22, 1915. Serial No. 16,061.

To all whom it may concern:

Be it known that I, GEORGE H. ELLIS, a citizen of the United States, residing at St. Paul, in the county of Ramsey and State of Minnesota, have invented certain new and useful Improvements in Heat-Insulating Units; and I do hereby declare the following to be a full, clear, and exact description of the invention, such as will enable others skilled in the art to which it appertains to make and use the same.

My present invention has for its object to provide an improved heat insulating unit adapted for very general use, but particularly adapted for use in connection with refrigerator cars and the like; and to such ends, generally stated, the invention consists of the novel devices and combinations of devices hereinafter described and defined 20 in the claim.

The present application is filed as a division of my Patent 1,187,197, issued of date, April 27, 1915, and entitled "Refrigerator car floor".

25 The improved heat insulating unit consists of a flexible water-proof envelop and a non-waterproofed heat insulating filler incased in the envelop and protected thereby from moisture. Preferably, the envelop is 30 made from a light weight asphalt roofing which is not only water-proof but is, in itself, a good heat insulating material; and the filler is preferably an insulating vegetable fiber, such as flax, and advisably is a flax product known to the trade as "flaxlinum". This latter noted product has a high heat insulating capacity.

It is a well-known fact that flax or other vegetable fiber, or for that matter, all heat 40 insulating materials, have a much higher heat insulating efficiency when dry than when wet. It is also a well-known fact that flax and other vegetable fibers will sour when wet. Experience has further shown that 45 all water-proof materials applied to these insulating fibers materially decrease the heat insulating quality thereof. Hence, the obvious importance of applying a water-proof envelop around a non-water-proofed 50 filler or heat insulating body. It is of the

utmost importance that the envelop be made of flexible material, first, because the envelop must be formed around the filler, or formed in shape to receive the filler by bending, and furthermore, because a flexible envelop provides for closer joints between adjacent assembled units. 55

In the accompanying drawings which illustrate the invention, like characters indicate like parts throughout the several 60 views.

Referring to the drawings:

Figure 1 is a perspective view showing the completed heat insulating unit looking at the top thereof; and 65

Fig. 2 is a perspective view of the unit looking at the bottom thereof, with some of the parts of the envelop broken away and opened up.

The flexible water-proof envelop is indicated by the numeral 1 and the fiber filler is indicated as an entirety by the numeral 2. As shown, the said filler is built up out of felted fibrous heat insulating sheets 2^a and interposed strips 2^b, which parts are 70 spaced so as to form air channels 2^c. The sheet from which the envelop is formed is bent around the filler. To form the envelop, its edges, at one side, are overlapped directly with each other, while the edges 75 at the other side are brought over and overlapped with the first noted overlapped edges. The said overlapped edges are cemented together and to the overlapped portions of the body of the sheet, preferably 80 by the use of suitable water-proof cement, and thus the envelop is made so that it will effectively exclude moisture from the filler, and the filler will always be kept in its dry condition, regardless of the amount of moisture 85 to which the exterior of the envelop is subjected. 90

This improved envelop has come into extensive use in refrigerator cars, and elsewhere, and has been found highly efficient 95 for the purposes had in view. It is of small cost and may be very conveniently applied in various places, such, for example, as between the joist of rafters or sills of the floor, walls or ceiling of a refrigerator car, or 100

other inclosure where it is desired to prevent the passage of heat, either inward or outward.

What I claim is:

- 5 A heat insulating panel or unit comprising an envelop made of flexible water-proof material, and a non-water-proofed heat insulating filler incased in said envelop and protected thereby from moisture, the said

envelop being folded around said filler and 10 having overlapped edges.

In testimony whereof I affix my signature in presence of two witnesses.

GEORGE H. ELLIS.
